HEATING DEVICE

John L. Mohun, Chicago, Ill.

Application September 16, 1940, Serial No. 357,014

10 Claims. (Cl. 183—32)

My invention relates to heating devices and more particularly to devices which clean and humidify the heated air arising from an enclosed heat source within a room, such as a convector, without seriously impeding the flow of air.

Many homes and offices employ convectors to transfer the heat from hot water or steam to the room air. These units are compact, occupying relatively little space, and as the name implies, operate largely by convection, rather than by combined convection and radiation as is the case with ordinary radiators. To operate properly these units should be surrounded by a shell extending above the convector, which directs the course of the heated air and creates a draft in a manner somewhat similar to a chimney. By reason of this principle of operation these convectors cause the air to move with considerable velocity as compared to ordinary radiators, and so increase the amount of dust and dirt suspended in the moving air, which is harmful not only to the occupants of the room but also to the furnishings.

Experiments have shown that the use of filters will not satisfactorily correct this condition, as filters thick enough to remove the dust offer a considerable resistance to the air and so decrease the efficiency of the convector unless mechanical means of drawing air through the unit are provided.

An object of my invention is, therefore, to provide an inexpensive device which will remove dust and dirt from the air passing through a heating device without greatly increasing the resistance to the air flow.

Another object is to provide an improved humidifier particularly adapted for use in connection with enclosed convectors.

Another object is to provide an air cleaning device which may be easily installed in existing convector units, and which may be easily cleaned by ordinary means.

Another object is to provide a convector enclosure of improved and simplified design which will clean and humidify the air and control the proportions of fresh and recirculated air discharged into the room.

These, and other objects, will become apparent from the following descriptions and from the drawings in which

Fig. 1 is a partially sectioned front elevation of one form of my device;

Fig. 2 is a vertical sectional view taken along the line 2—2 of Fig. 1;

Fig. 3 is a horizontal sectional view taken along the line 3—3 of Fig. 1;

Fig. 4 is a vertical sectional view of a modified form of my device adapted for ready removal or insertion in existing convector enclosures;

Fig. 5 is a horizontal sectional view taken along the line 5—5 of Fig. 4;

Fig. 6 is a perspective view of the removable portion of my device shown in section in Fig. 4;

Fig. 7 is a front elevation of another modification of my device having means of mixing and cleaning fresh and recirculated air;

Fig. 8 is a vertical sectional view taken along the line 8—8 of Fig. 7; and

Fig. 9 is a vertical sectional view taken along the line 9—9 of Fig. 7.

Referring to Fig. 1 my device comprises a shell generally designated 11, a convector 12, a humidifier 13, and scrubbers 14 arranged within the shell 11 above the convector 12. The shell 11 is a rectangular box-like structure fitting over the convector 12, which is supported above the floor in any convenient manner, as by a hanger 16 attached to the adjacent wall. The height of the shell is variable but will ordinarily extend upwardly approximately to the level of the window stool or slightly below, the enclosed space above the convector ordinarily being vacant. The shell 11 is provided with a removable front panel 17 which carries the humidifier 13 and has an air outlet 18 in its upper portion covered with a grill 20.

The lower edge of the removable panel 17 is provided with a plurality of projections 19 which cooperate with flange-like receivers 21 to retain the lower edge of the panel in the plane of the front of the shell 11. The projections 19 are formed of metal strips, one end of which is attached adjacent to the lower edge of the removable panel 17. The strips are bent inwardly and downwardly forming lower legs parallel to the upper legs and extending below the lower edge of the panel. The receivers 21 are angle sections, one leg of which is attached to the inner wall of the shell 11 slightly above the top of the convector 12. The upper legs of the receivers are substantially horizontal and extend inwardly from the shell. Openings are formed in the horizontal legs to receive the lower legs of the corresponding projections 19. The removable panel 17 is also provided with spring clips 22 which cooperate with the sides or top of the shell 11 to retain the removable panel 17 in place. The panel 17 may be removed by drawing the upper portion thereof outwardly to disengage the spring

clips 22 and then lifting the entire panel, which will disengage the projections 19 from the receivers 21, permitting access to the interior of the convactor.

The humidifier 13 comprises a container 23, fins 24, a filling opening 26, and a discharge opening 27. The opening 27 is formed in the removable panel 17 below the air outlet 18, the lower edge being curved inwardly and upwardly, forming a flange member 25. The container 23 resembles a shallow trough, attached along its edges to the outer surface of the panel 17, the upper edge of the container being above the opening 27. As it is essential that the joint between the container 23 and the panel 17 be water-tight, I prefer to attach the container to the panel by welding, although other suitable methods may be employed. A small opening 26 is provided in the upper portion of the container 23 through which water may be added. The inner surface of the panel 17 is provided with vertical inwardly extending parallel fins 24 adapted to rapidly transfer the heat from the warm air within the shell to the water in the container 23.

Scrubbers 14 are situated within the shell 11 in such manner that practically all of the air passing through the shell will come in contact with the surfaces of these scrubbers. The scrubbers consist of a rigid inner panel 28 covered on both sides with a loosely woven hairy felt-like material 29 having an irregular surface. Both the rigid panel 28 and the covering material 29 may be perforated, providing a multiplicity of relatively small openings extending through the scrubbers.

Two of these scrubbers will ordinarily be sufficient to adequately clean the air, the lower scrubber preferably extending inwardly and downwardly from the outer wall of the shell 11 adjacent to, but not in contact with, the convactor 12. The width of this scrubber is less than the width of the shell, thereby permitting the unobstructed passage of air between the end of the scrubber and the inner wall of the shell. The upper edge of the upper scrubber is preferably located adjacent to the humidifier fins and below the air outlet, but the scrubber does not extend over the top of the fins 24. The upper scrubber extends outwardly and downwardly in a direction opposite to the lower scrubber, and is narrower than the shell so that air may pass freely through the end of the scrubber and the outer wall of the shell. One of the principal purposes in providing scrubbers arranged in this manner is to direct the air rising from the convactor against as many scrubbing surfaces as possible without seriously increasing the resistance offered to the passage of air. My device will also function if the slope of the scrubbers is varied or if they are horizontal, but for reasons hereafter explained, the arrangement shown is preferred.

The scrubbers are retained in position by supports 31 having an L shaped cross-section. One leg of each support is attached to one side of the shell in suitable position. The other legs of the support 31 extend inwardly and form an inclined shelf on which the scrubbers rest. Rivets or bolts may extend through this leg and through the rigid panel 28 to attach the scrubbers to the supports or a projection may be formed on the lower end of each support to prevent movement of the scrubbers. The supports are, of course, provided upon each end of the shell and

are parallel to each other. It is not essential, however, that these supports be attached to the sides of the shell 11 as shown, for other methods of attachment are equally suitable. For example, the supports for one or more of the scrubbers may be affixed to the removable panel 17, or to the back of the shell 11 by modifying the supports in an obvious manner.

A deflector 32 is provided in the upper portion 10 of the shell and may comprise a sheet of metal 33 extending from the innermost upper corner of the shell 11 downwardly and outwardly to the outer wall of the shell 11 in such manner as to deflect the air through the opening 18. This deflector 33 may be supported in a manner similar 15 to that described in connection with the scrubbers 14.

The inner shell wall and sides, as well as the 20 inner surface of the deflector and the lower portion of the removable panel 17, are covered with a layer of loosely woven hairy felt-like material 29 similar to that used to cover the scrubbers 14. This material may be attached in any desired 25 manner as by riveting, stitching, glueing, or stapling, or if desired, may be removably attached by the use of spring clips or snap button fasteners.

The loosely woven hairy felt-like material 29 is commercially available under the trade name 30 of Ozite and differs from ordinary felt in that not all of the fibers forming the material are parallel to the plane of the material. It also has a design impressed upon its surface in relief making the surface irregular and allowing certain 35 of the fibers to extend outwardly at an angle to the plane of the material. Strength sufficient for handling is obtained by providing an intermediate layer of loosely woven burlap or similar material. When this material is perforated it 40 may be observed that it is practically impossible to obtain a perfectly clean cut, as the ends of the fibers or hairs comprising the material are deformed and after perforation will extend into the opening, forming a surface which is highly 45 efficient in removing dust from the air.

The operation of my device is apparent from the foregoing description, as it will be seen that air heated by the convactor 12 will rise upwardly 50 through the enclosure and be discharged through the opening 18. During its passage through the enclosure it will be brought into intimate contact with the hairy felt-like material on the scrubbers and on the sides of the enclosure and will deposit 55 thereon its charge of dust and dirt. Portions of the rising column of air will also pass through the openings 30 in the scrubbers 14. These openings greatly reduce the resistance offered by the scrubbers to the passage of air, and in addition serve to more thoroughly clean the air passing 60 through them as the edges of the openings present a surface which is more highly effective in removing dust and dirt from the air than is the surface presented by the material itself.

The column of air rising from the convactor 12 65 will also pass upwardly between the fins 24 and past flange 25, drawing the water vapor within the container outwardly through the opening 27. As the upper scrubber slopes outwardly and downwardly from the upper edge of the fins 24 70 it aids in directing a large portion of the air between the humidifier fins, thereby increasing the efficiency of the humidifier. The fins 24, having a large surface area, will be quickly heated by the air and will transfer this heat to the water 75 in the container 23 by conduction.

Periodic cleaning of the scrubbing surfaces within the enclosure is, of course, necessary for when they have become sufficiently coated with dust and dirt their scrubbing efficiency is greatly reduced. Replacement of these surfaces is, however, unnecessary as the front panel 17 may be removed and the surfaces cleaned with an ordinary vacuum cleaner. This will remove substantially all of the dust and dirt deposited thereon and restores the scrubbing surfaces to their original efficiency.

With the type of construction above employed it is incidental whether or not the enclosure extends into the room or whether it is partially surrounded by the wall of the building, the latter type being known as a recessed convector, for in either case the interior of the enclosure is accessible through the removable front panel 17. It should be noted that the hairy felt-like material 29 does not extend around or over the fins 24 as the felt-like material is an insulator and would largely counteract the benefits obtained through the use of the fins.

The insulating qualities of the felt-like material, when disposed according to my invention, serve to increase the efficiency of the heating unit as the material 29, disposed along the rear or outermost wall of the shell, prevents the transfer of heat outwardly to the wall of the room. This is particularly important in instances where the unit is recessed into the wall, for unless the wall is specifically constructed contrary to customary practice the heating unit will occupy the stud space necessitating the elimination of insulation from this area. It is clear therefore, that in ordinary devices having no insulation on the rear or outermost wall the large temperature differential between the shell and building wall will result in excessive heat loss thereby largely counteracting the benefits ordinarily obtained by the use of convection heaters.

The material attached to the front and side walls within the unit also increases the efficiency as it substantially reduces the transfer of heat by conduction or radiation, or in other words, the heat units normally dissipated in this manner are no longer lost in an ineffective manner but are taken up by the air passing through the unit. This not only creates a stronger current through the device but also increases the available comfortable space within a room, for furniture and other articles which would normally be kept at a distance due to the excessive heat radiating from ordinary devices may be disposed closer to my device with less danger of overheating.

My invention may be easily adapted to existing enclosures by a modification of my device illustrated in Figs. 4, 5, and 6 which comprises essentially a frame, generally designated 34 carrying scrubbers, and adapted to be inserted in the normally vacant space above the convector within the shell. The subsequently described structure is shown as being applied to a specific type of convector enclosure or shell but it is to be understood that this modification is equally adaptable to other types of enclosures. Referring to Fig. 4 the unit comprises a convector 36, a shell generally designated 37, a removable frame generally designated 34 carrying scrubbers 38, and a deflector 39. The general appearance of the shell 37 is similar to that described in connection with Fig. 2, but in this modification the front panel is not removable. The humidifier 13 is also similar to that described in connection with Fig. 2.

The front section of the shell 37 is attached at each vertical edge to vertical strips of angle iron 41, which are in turn connected by laterally extending reinforcements, not shown, to the inner wall of the shell, the strips 41 acting as frame reinforcements. At least one side of the enclosure, designated 42, is attached to the inner wall of the shell by a hinge 43 and may be retained in its enclosed position by a spring clip 44, attached to one edge of the side 42 and cooperating with an angle iron support 41.

The removable frame, generally designated 34, comprises a panel 46 of light gauge metal maintained in a vertical position parallel to the rear wall of the shell 37 by supports, generally designated 47. The upper portion of the panel 46 may be bent inwardly at an angle to form a deflector 39.

The support members 47 may be formed from a relatively light gauge metal formed into a channel section, and comprise a vertical leg 48 and an inwardly extending upper leg 49, the angle between the upper and lower legs being such that the deflector 39 will be supported by the upper leg 49 in its proper position. The supports 47 extend beyond the lower edge of the vertical panel 46, and are bent inwardly to form legs 51 adapted to rest upon the upper surface of the convector 36. Portions 52 of these lower legs 51 also extend downwardly and engage the side of the convector 36 to prevent inward movement of the base of the frame, 34.

The deflector 39 extends outwardly and downwardly from the upper inner corner of the shell 37 to the vertical panel 46 and may be attached to the support members 47 by rivets 53 or by other suitable means. The scrubbers 38 are also supported within the enclosure by the support members 47, the positions of these scrubbers, relative to the convector and shell, being substantially identical with that described in connection with the scrubbers in Fig. 2, but in this modification are supported by U shaped members 53 attached to the support members 47 by rivets 54. The scrubbers 38 rest upon the inwardly extending arms of the U shaped support members 53 and may be held in place by crimping the ends of the arms over the end of the scrubbers or by riveting or other suitable means. The scrubbers consist of a panel 56 of rigid material covered on both sides with a layer of loosely woven hairy felt-like material 57 having an irregular surface and preferably provided with perforations 58 to decrease the resistance to the flow of air. The inner side of the deflector 39 and of the panel 46 are also covered with a layer of similar material.

The operation of my device is similar to that previously described. This modification is, however, adaptable for installation in existing units and may be easily removed for cleaning by opening the hinged side 42 and sliding the removable frame 34, carrying the deflector 39 and the scrubbers 38, outwardly. It is, of course, obvious that the removable frame can also be inserted in an enclosure of the type illustrated in Fig. 2 in which the front panel is removable. It is not, however, necessary to remove the frame 34 for cleaning, as access may be had through the hinged side 42. The support members 47, as well as the light gauge metal forming the vertical panel 46 and the deflector 39, should be somewhat resilient to overcome minor variations in the dimensions of the shell and to aid in holding the frame 34 in place.

It is often desirable to provide means of introducing fresh air into a room through a convector. This may be accomplished by an apparatus such as that illustrated in Figs. 7, 8, and 9, which is adaptable for use in circumstances where the convector is located below a window. The unit consists principally of a convector 59, a shell, generally designated 61, a fresh air conduit 62 communicating with the lower portions of the convector shell, a humidifier 13, and a scrubber 63. The shell 61 is a rectangular box-like structure telescoped over a convector 59, which is supported above the floor in any convenient manner as by legs 64. The front panel of the shell 61 has a room air inlet 66 below the convector 59, and has an air outlet 67 in its upper portion. If desired, the air outlet may be provided with an adjustable diffuser, 68.

A shell 61 is provided with a hinged top 69 which may suitably be approximately level with the window stool. A hollow back wall 71 extends upwardly from below the convector to a point well above the window stool and forms one side of the fresh air conduit 62. This hollow wall is filled with an insulating material 72, such as insulating board, to prevent the transfer of the heat from the convector enclosure to the fresh air conduit. The back wall 71 is bent outwardly at a point above the window stool forming an upper side or top 73 of the fresh air inlet. This top extends outwardly beyond the plane of the window sash and has a gasket 75 attached to its upper surface upon which the lower sash rail 74 of the window rests. A channel shaped member 76 rests upon the sill of the window and defines, in conjunction with side members, not shown, a receiver for a removable cartridge type filter 77. A wall plate 78 extends inwardly from the frame member 76 to the edge of the window stool and downwardly therefrom to a point below the convector 59. An upwardly extending flange 79 is formed on the wall plate 78 inwardly from the filter and cooperates with a check valve 81 to control the passage of air through the fresh air conduit 62. The check valve 81 is hingedly attached to the top 73 of the fresh air inlet and is operatively connected to an external handle 82. Movement of the check valve will, of course, cause the ends of the handle to describe a limited arc. Spring clips 83 are attached to the side of the shell and are adapted to engage the handle 82 of the check valve 81 at the outer limits of the arc to retain the check valve in a fully opened or fully closed position. The sides of the shell 61 may extend upwardly above the hinged top 69 forming the sides of the fresh air conduit 62, and may also extend inwardly to the wall piece 78, completing the enclosure.

A damper 84 is attached to a rod 86 which is journaled in the sides of the shell 61 below the convector 59 between the back wall 71 and the front panel of the shell 61. One end of the rod 86 extends through a side of the shell and is bent to form a handle 87 by means of which the position of the damper 84 may be adjusted, the handle being in frictional engagement with the side of the shell. The damper 84 is adapted to swing between the back wall 71 and the front panel of the shell 61, thereby controlling the amounts of fresh and room air drawn upwardly through the convector 59.

A deflector 88 is provided within the shell extending from the upper inner edge of the shell 61 downwardly and outwardly to the back wall

71, the upper edge of the deflector being above the air outlet 67.

The scrubber 63 comprises a rigid inner panel 89 having horizontal corrugations formed therein and a covering of loosely woven hairy felt-like material 91. The upper edge of the rigid inner panel is bent around a horizontal bar 92, the ends of which extend upwardly substantially parallel and adjacent to the sides of the shell 61, forming legs 93. The upper ends of the legs 93 are pivotally attached to pins 94 which extend through the sides of the shell 61 and support the scrubber. If desired mechanical means such as a fan 95 and motor 96 may be provided to force air through the unit. The motor 96 should be mounted above the deflector 88 to prevent interference with the passage of air through the unit. A humidifier 13, similar to that previously described, is attached to the front panel of the shell 61.

The deflector 88, the inner side of the back wall 71 below the deflector, the sides of the shell 61, and the portion of the front panel of the shell 61 lying below the humidifier fins 97 are covered with a loosely woven hairy felt-like material 98 similar to that used to cover the scrubber 63. The covering 98, as well as the scrubber 63, terminate above the convector 59 and are not in contact therewith.

It should be noted that the felt-like material, while similar to that previously described, is applied to the unit in a somewhat different manner and is, in this case, preferably attached by rivets or similar means in such manner that the material will form irregular plaits or folds along the inner surfaces, which increases the effective area of the scrubbing surfaces.

The operation of this device is, in many respects, similar to that previously described. Fresh air may enter through the filter 77 when the check valve 81 and the damper 84 are open. The fresh air, being cool, will tend to sink to the bottom of the fresh air conduit 62, and this tendency will not be counteracted by heat from the convector, as the transfer of heat to the fresh air is prevented by the insulation 72 in the hollow back wall 71. Upon reaching the bottom of the enclosure the fresh air will be drawn upwardly together with room air which enters the enclosure through the room air inlet 66, through the convector 59, and will be discharged through the air outlet 68. Obviously, the amounts of fresh and room air admitted to the unit may be controlled by the damper 84 and the check valve 81. As the air passes upwardly it comes in intimate contact with the surface of the scrubber and the felt-like material attached to the walls of the enclosure, where it will deposit the entrained dust or dirt. As previously mentioned, the fan 95 and the motor 96 are not, in all cases, essential, but may be used if desired on this or other modifications of my device.

Under certain conditions it has been found that the heated room air may be drawn out of the room through the air inlet, as for example, when a strong wind is blowing from the other side of the building, causing a partial vacuum on the lee wall, or when an actual static pressure has been built up within the room. This action may be prevented by disengaging the handle 82 of the check valve 81 from the spring clips 83, allowing the check valve 81 to swing freely. The relatively slight pressure exerted by the incoming fresh air will ordinarily be sufficient to swing the check valve 81 to an open position, and allow

the fresh air to pass downwardly through the fresh air conduit 62 into the unit. If, however, the pressure should be reversed and the air starts to flow in the opposite direction the check valve 81 will swing shut against the flange 79, effectively preventing the loss of heated air. This operation of the check valve is, of course, prevented by holding the valve in a completely open or completely shut position by means of spring clips 83. As the air pressures involved are very slight the check valve 81 should be formed of a light metal such as aluminum, and covered on its outer face with a layer of hairy felt-like material to scrub the incoming air. Proper balance may be obtained by adjusting the position and weight of the handle 82, the adjustment being such that the valve remains closed at zero pressure.

It is, of course, obvious that many modifications may be made in the specific embodiments previously described with reference to Fig. 2, for example, the lower scrubber may be attached to the removable front panel 17, rather than to the rear wall of the shell, so that both scrubbers will be removed with the front panel or both scrubbers may be attached to the rear wall. Furthermore, any one of the units herein described may be connected to a fresh air outlet such as that shown in Fig. 8 in an obvious manner, or if desired, the fresh air inlet may comprise an opening through the building wall in a suitable location.

The foregoing detailed description has been made in compliance with section 4888 of the Revised Statutes, but as modifications may be made without departing from the scope and spirit of my invention I do not wish to be limited except by the scope of the appended claims.

I claim:

1. In a heating device comprising a convactor and a shell of substantial height telescoped over the convactor and having an air outlet in the shell above the convactor, a humidifier associated with the outer wall of the shell above the convactor having vertical parallel heat transfer fins extending into the shell and a baffle within the shell above the convactor, said baffle sloping up towards said fins, and having a surface formed of dirt absorbing material.

2. In an air heating and cleaning device comprising a convactor, and a shell telescoped over the convactor and having an air inlet below the convactor and an air outlet above the convactor, a humidifier associated with the shell and having fins extending inwardly into the path of the air and an external container, the container having a wall associated with the fins and communicating with the interior of the shell, a baffle within the shell above the convactor and sloping up towards said fins, and a layer of hairy felt-like material covering the baffle and substantially all of the inner surfaces of the shell above the convactor to provide scrubbing surfaces.

3. In an air heating and cleaning device, a convactor, a shell telescoped over said convactor, an external water container on said shell having an opening communicating with the interior of said shell, vertical fins attached to the inner wall of said container in parallel relation below said opening, and a sloping scrubber having its upper edge adjacent the upper end of said fins whereby a large portion of the heated air rising from the convactor is directed against said fins.

4. In an air heating and cleaning device, a convactor, a shell telescoped over said convactor, an L-shaped support within said shell, one leg of

said support resting on the convactor and the other leg being substantially parallel to a wall of the shell, angularly disposed arms attached to said support, and scrubbing means attached to 5 said arms, said scrubbing means comprising a panel of air impervious material extending angularly into the path of air rising from the convactor and covered with a dry felt-like material adapted to remove dust from the air by contact, 10 said shell having normally closed openings through which the support, arms and scrubbers may be removed as a unit.

5. In a heating device, a convactor, a shell of substantial height telescoped over the convactor having an air inlet and an air outlet and a 15 humidifier, said humidifier comprising a container, solid metal fins integral with one wall of the container extending into the shell above the convactor, the container being attached to the outer surface of the shell but in communication with the air within the shell, and means covered with felt-like material for directing air flowing across said convactor onto said fins.

6. In a heating device, a convactor, a shell having an air outlet telescoped over the convactor, and a humidifier associated with a wall of the shell below the air outlet but above the convactor, said humidifier comprising a container adapted to hold water attached to the outer surface of the shell communicating with the interior of the shell through a vapor discharge opening formed therein, a flange on the bottom edge of the opening extending upwardly and inwardly for directing air flowing across said convactor around said vapor discharge opening for entraining vapor from said humidifier, and parallel vertical fins associated with the container extending into the shell, the upper edges of the fins being below but adjacent to the flange.

7. In an air cleaning and heating device, comprising a convactor and a shell telescoped over said convactor, a removable frame within the shell above the convactor, and a plurality of air scrubbing means fixed to said frame, said frame comprising a back plate, a top plate extending upwardly and forwardly to form a deflector, means for securing said air scrubbing means to the front face of said back plate below said deflector plate, said shell having a normally closed opening through which the frame and scrubbing means may be removed as a unit.

8. An air heating and humidifying device comprising a convactor, a shell enclosing and extending a substantial distance above said convactor, said shell having a flat upright wall portion above said convactor and having an air inlet opening below said convactor and an air outlet opening above said wall portion, and a 55 box-like member having a side wall, two end walls, a bottom and a top, the edges of said end walls and said bottom being fixed to said wall portion whereby said box-like member and said wall portion cooperate to form a water receptacle, the top of said box-like member having a small opening therein for the insertion of water into said receptacle, and said wall portion having a large opening therein immediately below the top of said box-like member for the free escape of water vapor from said receptacle into said shell, and a small deflector lip extending inwardly and upwardly from the lower marginal edge of said last-named opening for deflecting air around said last-named opening for entraining vapor from said receptacle.

9. In a device of the class described, a convector, a shell of substantial height having front and rear walls telescoped over the convector, the front wall of said shell having a discharge opening adjacent its upper end and above said convector, an air deflector extending from immediately above said discharge opening downwardly and rearwardly to the back wall of said shell, a humidifier mounted on the front of said front wall and having a filling opening in its top wall, the front wall of said shell being provided with a vapor discharge opening opposite the upper portion of said humidifier, the lower marginal edge of said opening being curved inwardly and upwardly for deflecting air flowing through said shell around said vapor discharge opening for entraining the vapor from said humidifier, vertically arranged heat-conducting fins secured to the rear side of said front wall opposite said humidifier and extending rearwardly therefrom, means for directing air passing across said convector onto said fins and for creating a turbulence in said air, and felt-like material secured to the inner surfaces of the front and back walls of said shell and to said means and to the under side of said deflector for scrubbing air passing through said shell and for heat insulating said shell.

10. An air cleaning device for use in an air heating and scrubbing construction having a convector, a shell extending above said con-

vector having a discharge opening in the front wall at the upper end thereof and having a humidifier on said front wall provided with a heat conducting portion, said device comprising a panel having an upright portion adapted to fit against the back of said shell and a sloping top portion at the top of said upright portion and adapted to extend across the upper portion of said shell to the front of said shell above said opening, a plurality of baffle members carried by said panel, one of said baffle members being contiguous to and extending forwardly from said upright portion, an adjacent one of said baffle members spaced from said upright portion and extending forwardly therefrom and so constructed and arranged that when in use will deflect air passing upwardly from said convector onto said conducting surface for heating said humidifier, and a covering of dry felt-like dust collecting material for said baffle members and the front of said panel, said baffle members being provided with a plurality of openings therethrough whereby a portion of the air moving upwardly from said convector will pass through said baffle members and felt-like material thereon, respectively, and the remaining portions will flow around said baffles in contact with said felt-like material thereon for removing dust from said air.

JOHN L. MOHUN.
